UNITED STATES PATENT OFFICE

AMOS DURBIN PRITCHARD, OF CHICAGO, ILLINOIS, ASSIGNOR TO WESTERN ELECTRIC COMPANY, INCORPORATED, OF NEW YORK, N. Y., A CORPORATION OF NEW YORK

DISTRIBUTING SYSTEM

Application filed April 30, 1927. Serial No. 188,030.

This invention relates to distributing systems, and more particularly to an electric wiring distribution system for building construction.

5 In the construction of factories and large office buildings the present-day general use of concrete to reduce fire risk and obtain strength and durability has rendered the problem of electric wiring a difficult one, due to the inherent difficulty encountered in making subsequent alterations and extensions. For this reason it has been the practice heretofore to determine in advance the probable need and location of outlets for power, telephone, lighting, and other lines so as to reduce to a minimum the subsequent alterations or extensions necessary. However, in some instances it is inconvenient or almost impossible to definitely determine in advance the precise locations where outlets may ultimately be required.

10 The principal object of the present invention is the provision in building construction of an improved and economical system whereby electrical power, lighting, telephone or other service may be readily and conveniently supplied to any position within the building where the subsequent need thereof may arise.

15 30 In accordance with the general features of the invention as embodied in concrete floor construction, wooden sleeper strips arranged in parallel formation and spaced at suitable distances apart are embedded in the concrete floor slab in such manner that the upper surfaces thereof are flush with the surface of the concrete and serve as a means for securing or supporting the flooring which may comprise wooden blocks, tile, linoleum, etc. 25 35 40 45 Grooves provided on the undersides of these strips terminate in trenches or main ducts, such as are usually provided in building construction for housing power, light, telephone, gas, compressed air or other lines. As the need arises a line is run from the main duct

through the groove in the sleeper strip closest to the position where the service is required and then upwardly through openings then made in the sleeper strip and the flooring.

50 Other features and advantages of the invention will become apparent from the following detail description, reference being had to the accompanying drawings, wherein

55 Fig. 1 is a diagrammatic plan view partly in section of a portion of a floor construction embodying the features of the present invention;

Fig. 2 is a fragmentary transverse vertical section taken on line 2—2 of Fig. 1;

60 Fig. 3 is an enlarged perspective view of a portion of the structure shown in Fig. 1, and

65 Fig. 4 is an enlarged transverse section through one of the sleeper strips.

The invention is herein illustrated and described in connection with floor construction. It should be understood, however, that the features of the invention are equally applicable to wall or ceiling construction.

70 Referring now to the drawings in detail, the numeral 10 indicates a portion of a floor slab constructed with the usual trench or main duct 11 (Fig. 2) for housing electrical or other service lines. Wooden channel members or sleeper strips 12 supported upon sheet metal strips 13 are embedded in the concrete 75 slab 10 in such manner that the upper surfaces thereof are in a common plane with the surface of the slab, as best shown in Fig. 3. The edges of the sleeper strips 12 are tapered, as indicated at 16 (Fig. 4), to insure maximum rigidity when embedded in the concrete. An upper floor layer which may be composed of wooden blocks 17 or other suitable material is laid over the concrete slab 10 and the sleeper strips 12. Grooves or ducts 18 extending lengthwise on the under sides of the sleeper strips 12 terminate in the main duct 11. These grooves are adapted to accommodate electrical power or other service 80 85 90

lines drawn through them from the main duct 11.

In Fig. 1, the dot and dash lines 20 indicate the location of an apparatus to which it may be desired to supply electrical current. Several of the blocks 17 immediately above the portion of the sleeper strip 12 closest to the machine are removed, after which access may be readily had to the groove 18 by cutting through the upper wall of the sleeper strip, as indicated at 21 (Fig. 2). Conductors carrying electrical current may then be readily drawn from the main duct through the groove 18. For this purpose, a removable plate 22 is usually provided over the main duct 11 so that access to the lines contained therein may be readily and conveniently had. After the connections have been made, the blocks 17 are grooved or otherwise formed and replaced in position so as to provide an opening, as indicated at 24 (Fig. 2) for the passage of the conductors therethrough.

From the above description it is obvious that the present invention provides a simple and economical system for the distribution of power, telephone or other service to any location upon a floor where such service may at any time be required. It should be understood also that portions of the sleeper strips 12 may be very readily removed and replaced by strips having straight edges when for any reasons it becomes necessary to do so.

Although only one specific embodiment of the invention has been herein illustrated and described, it should be understood that the invention is capable of other applications within the scope of the appended claims.

What is claimed is:

1. A concrete floor construction comprising a concrete slab and a member grooved on its under side and having a plane upper surface, said member being embedded in the concrete with its upper surface in a common plane with the upper surface of the concrete, and a removable upper floor layer supported upon the concrete and the grooved member.

2. In a service distributing system for buildings, a supporting slab having a member embedded therein, said member having a plane upper surface and being embedded in such manner that the upper surface of the member is in a common plane with the upper surface of the slab, the member being grooved on its opposite side to provide a passage for accommodating a service distributing line.

3. In a service distributing system for floors, a supporting slab, a removable upper floor layer engaging and supported upon the slab, and a plurality of sleeper strips having flat upper surfaces and having grooves on their under sides for housing service distributing lines, the sleeper strips being arranged in parallel and spaced relationship and embedded within the supporting slab in such manner that the upper surfaces thereof

are in a common plane with the engaging surfaces of the upper floor layer and the supporting slab, whereby service may be readily supplied to any position upon the floor by removing a portion of the upper floor layer and cutting through a sleeper strip at any point therealong to gain access to the service distributing lines contained therein.

4. A building construction comprising a supporting slab having a conduit member having a plane surface and embedded in the slab with said surface flush with the upper surface of the slab, said member having a longitudinally extending open groove on its under side for housing service distributing lines.

5. A building construction comprising a supporting slab, a removable covering engaging and supported upon the slab, and a conduit member having a plane surface and embedded within the slab in such manner that said surface is in a common plane with the engaging surfaces of the slab and the covering, said member being grooved on its opposite side to accommodate a service distributing line.

6. In a floor construction, a concrete slab having a conduit member embedded therein for housing service distributing lines, said conduit member comprising a pair of spaced side portions and an integral continuous top portion, the upper surface of the top portion being plane and disposed flush with the upper surface of the slab.

7. In a floor construction, a concrete slab having a wooden sleeper member embedded therein and adapted to receive securing means for flooring, said sleeper member comprising a pair of spaced side portions and an integral continuous top portion, the upper surface of the top portion being substantially flat and in a common plane with the upper surface of the slab, and a plate member engaging the bottom edges of the side portions for cooperating with the sleeper member to provide a lined passageway for housing service distributing lines.

8. In a floor construction, a concrete slab having a conduit member embedded therein comprising a substantially flat top portion and a pair of spaced downwardly extending side portions tapering outwardly therefrom, the upper surface of the top portion being in a common plane with the upper surface of the slab and being adapted to receive securing means for flooring.

9. In a floor construction, a concrete slab having a wooden conduit member embedded therein and comprising a substantially flat top portion and a pair of spaced downwardly extending side portions of substantial thickness, the upper surface of the top portion being in a common plane with the upper surface of the slab and being adapted to receive securing means for flooring.

10. In a floor construction, a floor slab having a conduit member embedded therein, said conduit member comprising an upper portion having a plane upper surface positioned flush with the upper surface of the floor slab and a pair of spaced downwardly extending side portions of substantial thickness, the conduit member being adapted to receive securing means for flooring.

10 In witness whereof, I hereunto subscribe my name this 19th day of April, A. D. 1927.

AMOS DURBIN PRITCHARD.
